UNITED STATES PATENT OFFICE.

SIDNEY HOWE SHORT, OF DENVER, COLORADO, ASSIGNOR, BY DIRECT AND MESNE ASSIGNMENTS, TO THE UNITED STATES ELECTRIC COMPANY, OF SAME PLACE.

SPRING-JACK FOR ELECTRIC RAILWAYS.

SPECIFICATION forming part of Letters Patent No. 379,081, dated March 6, 1888.

Application filed February 16, 1887. Serial No. 227,797. (No model.)

To all whom it may concern:

Be it known that I, SIDNEY HOWE SHORT, of Denver, in the county of Arapahoe and State of Colorado, have invented a new and useful 5 Improvement in Spring-Jacks for Electrical Railways; and I do hereby declare that the following is a full, clear, and exact description of the same.

My invention relates to electrical railways of 10 that class in which a single sectional conductor is used, and is an improved spring-jack for connecting the ends of the sections of the conductors.

The invention is adapted to electrically connect the ends of the sectional conductor and to permit the passage of the current-collector, so as to deliver through the same the necessary amount of electricity to drive the car.

In the drawings, Figure 1 represents a section in a plane at right angles to the direction of the slot of the conduit. Fig. 2 is a section in a plane parallel with the slot. Fig. 3 is a section through the contact-plates parallel with the surface of the roadway.

25 In Fig. 1, E represents a bracket which has at its lower end a spring, g, bolted to it by the bolt m. At the top of the spring g is one of the contact-plates, a, having a projecting hood to the left, d. The upper end of the bracket

30 F is cup-shaped, as shown at e, and a coiled spring, S, is placed within this cup or hollow cylinder and made to press against the plate a under the hood d. This coiled spring S tends to drive the plate a and spring g toward the

35 right, but is stopped by the plate b, with which it comes in contact at n. The plate b is stationary by its support I. In order to prevent leakage to the ground from these circuit-closers, they are supported on bell insulators I I', of

40 glass or other insulating material, and are clasped to the casting F and plate b. I prefer to use two insulators on each side of this circuit-closer, as shown in Fig. 3 at I, I', I², and I³. These insulators are carried on pins which

45 are fastened to the pin-supports J and J'. These pins are carried by the frame K.K, which is arranged to be attached either to the conduit or cross-ties of the road-bed.

One end of the cable w enters the binding-

post P of the casting F. The current enters 50 through this cable, passes through the casting F, the spring g, and coiled spring S to the contact-plates a and b, then out through the binding-post P', which is fastened to the plate b and to the cable w.

55 In Fig. 3 the broken line R represents the path of the current-collector. This collector is made of an insulating-bar, having on either side strips of copper connected through the motor on the car. As it moves into the circuit-closer through the notches o and o' in the ties along the line of R, it wedges itself between the faces of the curved plates a and b. The spring S allows the plate a to move upward, and the contact at n, between the plates a and 60 b, is broken. Plate a, however, will be in contact with one of these narrow strips and plate b in contact with the other. The current will no longer pass through the contact at n, but will find a path through the motor of the car. 65

70 When the current collector has passed from between the plates a and b and out at the left-hand side, the spring S will immediately force the plate a toward the stationary plate b, making contact at n and closing the circuit. The 75 contact n is always electrically good, because the sliding of the current-gatherer over the faces a and b keeps them bright and clean.

75 When the plate a moves back toward P in Fig. 1, the hood d passes over the cylinder e 80 and returns to its original position as the spring S is released. This hood is intended as a protection to the spring S from the mud and snow which may fall through the slot which is just about it.

85 I claim as my invention—

1. In an electric railway having a single sectional conductor and a current-collector, a spring-jack arranged between the ends of the sectional conductor, consisting of metallic faces 90 a b, connected to the adjoining sections of the conductor, said faces being normally in contact, one movable and the other fixed, and arranged in the line of movement of the current-collector, to be separated by the said collector 95 acting directly upon them, substantially as described.

2. In an electric railway having a single sec-

5
tional conductor, a spring-jack arranged between the ends of the sections, consisting of metallic contact-faces *a* and *b*, one of said faces being stationary and the other being supported so as to have lateral movement with a suitable spring for returning and keeping it normally in contact with the fixed face, substantially as described.

10
3. In an electrical railway having a single sectional conductor, a spring-jack arranged between the ends of the sections, said jack consisting of two contact-faces, one of said faces being fixed and the other being supported upon a spring, *g*, and adapted to have lateral movement away from the fixed face, and a spring, *S*, in rear of the moving part adapted to keep it normally in contact with the fixed face, substantially as described.

15
4. A spring-jack adapted to be used between the ends of the sections of an electrical railway, having a single sectional conductor consisting of metallic contact-faces, one of said faces being fixed and the other being supported upon spring *g*, so as to have lateral movement, a coil-spring bearing against the rear of said face and being partially contained within a covered pocket, and a flaring hood extending from the said contact-face rearwardly, whereby the spring is protected, substantially as described.

20
25
30
35
40
45
50
55
3. A spring jack for a single sectional conductor of an electrical railway, consisting of

two parts, each of said parts being secured to bell-shaped insulators, substantially as described.

6. A spring-jack having a single sectional conductor of an electrical railway, consisting of two parts, each of said parts being secured to a bell-shaped insulator, and the insulator secured to a suitable support for working, substantially as described.

7. A spring-jack for the ends of the sections of the single sectional conductor of an electrical railway, consisting of a fixed contact-face provided with stationary binding-post, a movable contact-face supported from a fixed bracket by a spring and in electrical connection therewith, and a fixed binding-post upon said bracket, substantially as described.

8. In an electrical railway, a spring-jack between the sections of the conductor, consisting of opposing faces normally in contact, one movable and the other fixed, and arranged to be separated by the passage of the current-collector between the opposing faces, substantially as described.

In testimony whereof I have signed my name to this specification in the presence of two subscribing witnesses.

SIDNEY HOWE SHORT.
